UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

CONTROLLER.

SPECIFICATION forming part of Letters Patent No. 766,327, dated August 2, 1904.

Application filed February 4, 1903. Serial No. 141,836. (No model.)

To all whom it may concern:

Be it known that I, FRED B. COREY, a citizen of the United States, residing at Schenectady, county of Schenectady, State of New York, have invented certain new and useful Improvements in Controllers, of which the following is a specification.

My invention relates to controllers designed especially for railway use, and relates more specifically to the construction of the reversing-switch in said controller.

The object of my invention is to provide a reversing-switch having great simplicity of construction, which shall be very efficient in operation, and which may be adjusted to suit various sizes of motor equipments.

The invention comprises a reversing-switch cylinder built up of a plurality of segmentally-shaped interchangeable units, each of said units carrying sufficient contact-segments to act as a complete reversing-switch for a motor equipment having a predetermined number of motors.

More specifically stated, my invention comprises a reversing-switch having one or more semicylindrical members mounted so as to embrace the operating-shaft of said reversing-switch, each of said semicylindrical units being made up of insulating material molded into the proper shape having the connecting members of the contact-segments molded into the insulating material.

The switch is especially adapted for one, two, or four motor equipments, one of said semicylindrical units forming a complete reversing-cylinder for one or two motors, as desired. Two of said semicylindrical units when fastened to the shaft of the reversing-switch in such a manner as to embrace the said shaft and almost completely surround the same form the reverse-cylinder for a two or four motor equipment, as desired, it being understood that the required number of contact-segments are carried by the insulating material and the required number of contact-fingers are provided to engage the said contact-segments.

In the accompanying drawings, which illustrate the preferred embodiment of my inven-

tion, Figure 1 is a front elevation of a controller with the front cover removed. Fig. 2 is a plan view of said controller having a part of its cap-plate broken away to show the relative position of the reversing-switch. Fig. 3 is a section through the reversing-switch cylinder on the line 3 3, Fig. 1. Figs. 4 and 5 are side and end views, respectively, of the connecting member for the contact-segments; and Fig. 6 is a diagrammatic representation of the connections between the contact-segments of a reversing-switch for a single-motor equipment.

Referring now to the figures of the drawings, A represents a controller-casing having a cap-plate B. Mounted within the controller-casing A in the customary relationship are the controlling-switch cylinder C and the reversing-switch cylinder D.

The customary interlocking mechanism between the controlling-switch cylinder and the reversing-switch cylinder is indicated by a. The shaft c of the controlling-switch cylinder and the shaft d of the reversing-switch cylinder project through the cap-plate and are adapted to receive the operating-handles, only one of which—namely, the handle d' of the reversing-switch—is shown in the figures.

The reversing-switch D is built up of a plurality of segmentally-shaped or semicylindrical interchangeable units h and h', made of insulating material and molded into the desired shape. These semicylindrical units, as is clearly shown in the figures of the drawings, are adapted to embrace the reversing-switch shaft d and are fastened thereto by means of bolts k, which pass completely through said shaft. Embedded in the insulating material of the semicylindrical units are the specially-constructed connecting members for the contact-segments. These connecting members p are preferably made of heavy copper wire and are formed into the shape shown in Figs. 4 and 5. The ends of said connecting members are flattened, so as to form the heads p', and said heads are turned to one side, as shown in said figures and also in Fig. 3. The said heads p' are tapped at s, so as to receive the screws which are used for holding the remov-

able contact-segments in their proper positions. During the process of molding the semicylindrical units the connecting members p are embedded in the insulating material in such a manner that the faces of the heads p' are flush with the outer surface of the said semicylindrical unit. The connecting members p are made in two lengths and are arranged as shown in Fig. 6, which illustrates diagrammatically the connections for the contact-segments in a reversing-switch for a single-motor equipment. It will be noticed in said Fig. 6 that the contact-segments t' , which are on one side of the switch, are connected together in pairs, adjacent contact-segments being connected together to form each pair, while on the other side of the switch on which the contact-segments t are mounted the alternate contact-segments are connected together.

In the figures of the drawings I have illustrated the proper size of reversing-switch to be used with a four-motor equipment, the switch shown being built up of two semicylindrical units each carrying contact-segments sufficient to form a complete reversing-switch for a two-motor equipment. It will be readily seen that in order to change the reversing-switch shown in the figures into a reversing-switch for a two-motor equipment it is only necessary to omit one of the said semicylindrical units and use a shorter bolt in place of the bolt k to fasten the remaining semicylindrical unit to the shaft d . For a single-motor equipment a unit of one-half the length of one of the units shown in the figures of the drawings, having its contact-segments mounted in the manner shown diagrammatically in Fig. 6, is used. For a one or two motor equipment a single row of contact-fingers f is all that is required; but for a four-motor equipment a double row of contact-fingers, mounted as shown in Figs. 1 and 2, is the preferred construction.

Although I have shown my reversing-switch as having removable contact-segments, my invention is not necessarily limited to such a construction, for the segments could readily be formed integral with the connecting members. The connecting members may be made, if so desired, of sheet-metal punchings of the desired shape and bent into the proper form to accomplish the purpose for which the heavy-wire connecting member shown in the drawings is used.

What I claim as new, and desire to secure by Letters Patent of the United States, is—

1. A reversing-switch cylinder comprising

a plurality of segmentally-shaped interchangeable units, each of said units carrying sufficient contact-segments to act as a complete reversing-switch cylinder for a predetermined number of motors.

2. A reversing-switch cylinder comprising one or more semicylindrical interchangeable units adapted to embrace the operating-shaft of the switch, each of said semicylindrical units being formed of molded insulating material into which the connecting members of the contact-segments of the switch are embedded.

3. A segmentally-shaped unit for a reversing-switch cylinder formed of molded insulating material and having a plurality of replaceable contact-segments mounted thereon, the connecting members for said contact-segments being embedded in said insulating material.

4. In a reversing-switch, two series of contact-fingers, and a relatively movable member comprising two interchangeable semicylindrical units of insulating material, each of said units carrying a plurality of contact-segments adapted to engage one of said series of contact-fingers.

5. A reversing-switch comprising a plurality of contact-fingers, and a relatively movable member made up of a plurality of semicylindrical units of molded insulating material, each of said units carrying a plurality of contact-segments to engage said contact-fingers, said segments having their connecting members embedded in said insulating material.

6. In a reversing-switch for a plurality of motors, a plurality of interchangeable semicylindrical units of molded insulating material, each of said semicylindrical units having a sufficient number of contact-segments to allow it to be used as a complete reversing-switch cylinder for a smaller number of motors.

7. A reversing-switch cylinder comprising a shaft, and a plurality of interchangeable semicylindrical units of molded insulating material fastened to said shaft, each of said units having a sufficient number of contact-segments to allow it to be used as a complete reversing-switch cylinder for a motor equipment having a predetermined number of motors.

In witness whereof I have hereunto set my hand this 3d day of February, 1903.

FRED B. COREY.
